Primary Examiner — Dana L Meyrow(57) **CLAIM**

The ornamental design for a bottle, as shown and described.

DESCRIPTION

FIG. 1 is a perspective view of the bottle.

FIG. 2 is a side view of the bottle shown in FIG. 1.

FIG. 3 is a top view of the bottle shown in FIG. 1; and, FIG. 4 is a bottom view of the bottle shown in FIG. 1.

The evenly broken lines shown in the drawings illustrate portions of the design that form no part of the claim. The dot-dash broken lines in the drawings define the bounds of the claim and form no part thereof. Separated portions of the bottle that are connected by a bracket indicate that a length is not claimed.
